Charles J. Hause,
INVENTOR
BY
Victor J. Evans
ATTORNEY

WITNESS: Fred W. Ely.

UNITED STATES PATENT OFFICE.

CHARLES J. HAUSE, OF ASBURY PARK, NEW JERSEY.

BAG HOLDER.

Application filed April 7, 1922. Serial No. 550,531.

To all whom it may concern:

Be it known that I, CHARLES J. HAUSE, a citizen of the United States, residing at Asbury Park, in the county of Monmouth 5 and State of New Jersey, have invented new and useful Improvements in Bag Holders, of which the following is a specification.

This invention relates to means for holding laundry bags while they are being filled 10 and is also applicable for use in holding nets or bags for other purposes.

The principal object is to produce a device of this nature which may be operated by the foot so that both hands may be free 15 after placing the top of the bag over the gripping members or jaws.

Another object of the invention is to produce a device which shall be simple of construction, cheap to manufacture, and highly 20 efficient for the purpose for which it is designed.

With these and other objects in view, the invention resides in certain novel construction, and combination and arrangement of 25 parts, the essential features of which are hereinafter fully described, are particularly pointed out in the appended claims, and are illustrated in the accompanying drawing, in which:—

30 Figure 1 is a front elevation of my net holder.

Figure 2 is a vertical sectional view of the same.

Figure 3 is a bottom plan view of the 35 same.

Figure 4 is a detail view of one of the holding jaws.

Like characters of reference refer to like parts in all views.

40 Referring to the drawing in detail, 10 represents a base which may be made of any suitable material, and which is provided with an aperture 11 through which projects one end of a bar 12 having a foot pedal 13. 45 Bar 12 is pivoted at 14 to the opposite side of the base 10, and at intermediate point passes through the knuckles 15 and 16. A 50 spring 17 which may be of any suitable type maintains the member 12 with the pedal 13 elevated.

The knuckles 15 and 16 are formed on the 55 ends of U-shaped frames 18 and 19 respectively, said frames being pivoted at 20 in any suitable manner and having their free ends bent upwardly as at 21 and extending

through the top of the base 10. The upright portions 22 are preferably tubular. The sack engaging jaws 23, two in number, are arranged at opposite sides, each jaw engaging with the uprights 22 of a respective 60 member 18 or 19. Each jaw comprises a twisted wire member having a central curved portion 23 and a pair of shanks 24 and the latter fitting into the bores of the respective uprights 22. The members 24 are made a 65 close fit for the tubes 22 and are therefore capable of a considerable amount of vertical adjustment to compensate for differences in the size of bags or nets.

It will be seen that by placing the foot on 70 the lever 13 and pressing down the jaws 23 and 24 will be drawn toward each other so that the top of the bag may be readily folded over them as shown in Figure 1.

Upon releasing member 13, spring 17 immediately returns the parts to normal position, or as nearly so as the width of the bag will permit, thereby firmly holding the bag in position to receive its contents, and leave both hands of the operator free for 80 the purpose of filling the bag.

While I have described what I deem to be the most desirable embodiment of my invention, it is obvious that the details may be varied without in any way departing from the spirit of my invention, and I therefore do not limit myself to the exact details of construction herein set forth nor to anything less than the whole of my invention limited only by the appended claims.

What is claimed as new is:—

1. In a device of the class described, the combination of a base, a plurality of frames pivotally mounted therein, a pivotally mounted member connected to both of said frames, means for holding said member in a predetermined position, and a treadle for holding said member, uprights extended from said frames through said base, and bag holding elements adjustable on said uprights.

2. A bag holder comprising a base, a pair of frames pivoted in said base, portions of said frames disposed horizontally within said base, a pivotally mounted member connected with said horizontally disposed portions, whereby movement of said pivotally mounted member will cause rocking of said frames as and for the purpose set forth.

3. A bag holder comprising a base, a pair

105

110

of frames pivoted in said base, portions of said frames disposed horizontally within said base, a pivotally mounted member connected with said horizontally disposed portions, whereby movement of said pivotally mounted member will cause rocking of said frames, and means for returning said piv-

otally mounted member and said frames to normal position as and for the purpose set forth.

10

In testimony whereof I have affixed my signature.

CHARLES J. HAUSE.
